UNITED STATES PATENT OFFICE.

FREDERICK FLETCHER BYINGTON, OF OAKLAND, CALIFORNIA.

GAGE ATTACHMENT FOR PRINTING-PRESSES.

SPECIFICATION forming part of Letters Patent No. 351,309, dated October 19, 1886.

Application filed November 4, 1885. Serial No. 181,859. (Model.)

To all whom it may concern:

Be it known that I, FREDERICK FLETCHER BYINGTON, of Oakland, in the county of Alameda and State of California, have invented 5 a new and useful Improvement in Gage Attachments for Printing-Presses, of which the following is a description.

Figure 1 is a perspective view showing the application of my invention to the platen of 10 a printing-press. Fig. 2 is a longitudinal section through line x x of Fig. 1, drawn on a larger scale; and Fig. 3 is a detail of the channel-plate.

My invention is in the nature of a gage attachment for the platens of job printing- 15 presses for fixing the position of the cards or blank sheets, so as to cause them to properly register in receiving the impression from the type.

20 In the drawings, A represents the platen of a press, which is provided, as usual, with the bail-shaped clamp-bars B B, that are pivoted to the side edges of the platen, and are swung down over the edges to clamp and hold the 25 sheets of paper that are placed upon the platen.

C is a curved spring, which at one end is turned at nearly right angles at a , and provided with two sharp points to engage with 30 the tympan-sheets. Through a slot in this flanged or turned edge there projects a tongue, b , connected to the end of the spring by clips that embrace the same, said tongue being used to retain the sheets of paper and cards and 35 prevent their slipping over the gage. The curved spring C slides adjustably through a slot or channel in a plate, D, which plate is bent to such curvature as to hold the spring in this channel to any desired adjustment.

40 To the under side of this plate, and closing the channel or slot, is riveted a plate, c , having a blade, d , projecting therefrom nearly at right angles. This blade serves to connect the spring-plate and spring to the platen by 45 being caught and held by frictional contact between the outer edge of the platen A and the inner edge of one of the bail-shaped clamp-bars B. To insure the tight holding of this blade against any tendency to drop out by the 50 jar of the press, the blade is slightly curved, so that it has a degree of elasticity, like a

spring, which holds it in place when clamped. When the spring-holding plate is thus secured, the spring, whose normal shape is curved, lies flat against the tympan-sheets, with the points 55 in the tympan-sheets just where the edge of the card or blank sheet s is designed to come. To adjust these points to a higher or lower position the spring C is simply slipped through the channel in the spring-plate, and as the 60 gage is adjusted close to the edge of the tympan, where the spring is secured, the spring, by reason of its curvature, turns at its free or back end under the platen, and out of the way. Where said spring lies on the tympan-sheet, 65 however, it lies perfectly flat against the same, this result being obtained by making the spring tapered or smaller at the end which forms the gage. A curved spring of uniform transverse dimension will not lie flat against a plain surface, for the reason that there is a cumulative tension from both ends toward the center that makes it buckle up at the center. The tapered construction of my spring causes the 70 tension to decrease constantly from the point 75 of connection at the holder toward the small end, and as the greater strength of tension overcomes the less each point on the spring is held flat by the superior tension of the part nearer the holder. 80

Among the advantages of my invention I may mention that there are no prongs to stick through the tympan-sheet and card-board beneath, which spoils the tympan-sheets and injures the surface of the card-board. With 85 this invention the card-boards are kept perfectly smooth. Again, it is very easily adjusted in place, for while the blade is being put between the clamp and platen the spring may be drawn out and the gage placed exactly where the sheet is to be held; also, when the gage is to be changed, it can be 90 changed to any extent, and instantly.

Having thus described my invention, what I claim as new is— 95

The curved spring-bars C, made tapering, as shown and described, in combination with a holder, D, as and for the purpose described.

FREDK. FLETCHER BYINGTON.
